DISPLAY CAP FOR A PRESSURIZED CAN

Neil S. Waterman, Stamford, Conn., assignor to Alberto-Culver Company, Melrose Park, Ill., a corporation of Delaware

Filed Oct. 1, 1964, Ser. No. 82,307

Term of patent 14 years

(Cl. D58—26)

FIGURE 1 is a perspective view of a display cap for a pressurized can, showing my new design;

FIGURE 2 is a front elevational view thereof;

FIGURE 3 is a side elevational view thereof;

FIGURE 4 is a rear elevational view thereof; and

FIGURE 5 is a top plan view thereof.

I claim:

The ornamental design for a display cap for a pressurized can, as shown.
